UNITED STATES PATENT OFFICE.

WILLIAM J. HEWITT, OF COYTESVILLE, NEW JERSEY.

CURTAIN-FIXTURE.

SPECIFICATION forming part of Letters Patent No. 551,862, dated December 24, 1895.

Application filed August 31, 1895. Serial No. 561,068. (No model.)

To all whom it may concern:

Be it known that I, WILLIAM J. HEWITT, a citizen of the United States, residing at Coytesville, in the county of Bergen and State 5 of New Jersey, have invented certain new and useful Improvements in Curtain-Fixtures, of which the following is a specification.

This invention relates to curtain-fixtures and to rollers for window and other shades 10 used for similar purposes, and the object thereof is to provide an improved support or fixture for curtains, portières or similar articles, which is simple in construction and operation, and which is adapted to support a 15 curtain or similar article in any desired position and allowing a part of the fixture to be lowered and raised in order to attach or remove the curtain or similar article, and also to provide means for adjusting the curtain, 20 &c., longitudinally of its support, and with this and other objects in view the invention consists in the construction, combination, and arrangement of parts hereinafter described.

The invention is fully disclosed in the following specification, of which the accompanying drawings form a part, in which—

Figure 1 is a side elevation of a part of my improved curtain-support, showing a curtain connected therewith. Fig. 2 is a rear view 30 thereof with a part removed to disclose interior construction. Fig. 3 shows an enlarged cross-section on the line 3 3, Fig. 4. Fig. 4 is a transverse sectional elevation on the same scale as Fig. 3, and Fig. 5 is a diagrammatic view illustrating the curtain pole or bar lowered for manipulation.

My invention consists, first, in the construction of the curtain-pole, and, second, in the combination therewith and with a suitable cornice, of means to raise and lower the pole for attaching, detaching, or otherwise manipulating the curtain.

I will first describe the construction of the curtain-pole.

In the practice of my invention I employ a 45 bar or pole A of the desired shape and material, preferably of wood, and which is of the length of any curtain pole or support required. It is constructed of two bars, or 50 preferably pieces of wood B B, each having a longitudinal and segmental recess C formed on the upper and inner side, and a vertical

side c, which bars, when juxtaposed and joined together by end pieces or plates D, provide a bar or pole having an intermediate 55 or longitudinal segmental groove E opening out of the top of the bar or pole thus formed, the sections B B being separated transversely to form a longitudinal slot F. The bottom of the groove E is circular in cross-section, and 60 the longitudinal slot F communicates with the longitudinal groove E throughout its length.

The means for connecting a curtain or other article with my improved pole or support may 65 consist of the spring-clamps G, of the usual or any preferred form of construction, provided with a link H, which extends upwardly through the slot F, and is secured at its upper end to or otherwise connected with a semi- 70 spherical or segmentally-formed block I, the convex surface of which is directed downward, and as will be understood, these links are free to move back and forth in the slot F, in which operation the semispherical blocks 75 I are supported and move upon the curved bottom surface of the longitudinal groove E.

It will be noticed that the groove E is wider at its open top than the diameter of the blocks I, which provides means for inserting and removing the blocks, (the clamps G being readily detachable from the links, which latter can be drawn through the slot F,) or the removal of any one of them without disturbing the others, and without removing the end pieces D. This 80 I consider a great improvement of the prior constructions, as far as I know of them, as they involved the insertion of each of the blocks, one after the other, through the end of the groove, and the removal of a number to get 85 at the central ones. It will thus be seen that the curtain or other article may be drawn or gathered to one side or extended the full length of the pole, and I thus accomplish the object of my invention by means of a device 90 simple in construction and operation and one which is comparatively inexpensive. If it is desired to use this part of my invention disconnected from a molding or housing and the means hereinafter described for raising and 95 lowering the pole, I can also secure to or connect with the front side of the pole an ornamented piece of molding, which may be of any desired form or configuration in cross-sec- 100

tion and which would preferably project slightly below the sections B B.

I, however, prefer to use the improvements in the pole in connection with the following, 5 which comprises the second portion of my invention.

I provide a suitable combined housing and cornice J, consisting of the front molding K, the top board L, end boards M, and rear board 10 N, which forms an inverted trough or housing O, in which the curtain-pole A is lodged when the curtains are in place, and this I secure to the wall, &c., P, as indicated in Fig. 4. Attached to the under side of the top board L are 15 two pulleys Q Q', in hangers R, and secured to the pieces B and crossing the groove E are cross-bars or pins S S' S'' S''', which brace the bars B B, together meditately of their ends, and from the cross-bars or pins S S' lead cords 20 T T' which pass respectively over the pulleys Q Q', both cords passing through a hole U in the end boards M, and downward convenient to the operator. It is clear that with this arrangement, by pulling on the cords the pole 25 A can be raised, and by releasing them it can be lowered, the curtain which is suspended from the pole by the clamps G being simultaneously raised or lowered, so that it can be manipulated as desired, and when raised the pole 30 and fixtures are entirely out of sight, thus enabling me to use rougher material in its construction than if it were to be exposed.

Instead of using the combined housing and cornice I can secure the means for raising and lowering the pole directly to the window-frame or to a cornice of the usual or desired construction without departing from the spirit of my invention.

Having fully described my invention, I 35 claim and desire to secure by Letters Patent—

1. A curtain pole or support comprising the two bars B, B, each having a longitudinal quadrantal and segmental recess formed in 45 one of its upper sides and a vertical side leading to the edge of said recess, the said bars being juxtaposed with their vertical sides opposed to form a longitudinal slot, the edges of the said recesses being aligned to form a 50 complete longitudinal groove opening out of

the top of the bar, combined with detachable plates for securing the ends of the bars together, segmental blocks supported in said groove and links depending from said blocks through said slot, the groove opening in the 55 bar being wider than said blocks, substantially as described.

2. A curtain pole or support consisting of two bars B, B, each provided with a longitudinal recess C, which is a segment of a circle, and a vertical side c, which bars, when juxtaposed, form a central longitudinal and segmental groove E, and a longitudinal slot F in the bottom which communicates with the groove, the groove opening out of the top of 60 the bars, combined with the segmental blocks I which are free to move in said groove, links secured to the blocks and extending downwardly through said longitudinal slot, and cross bars securing the bars B, B, together 65 between the ends of said latter bars, substantially as described.

3. A curtain support comprising a pole provided with means for detachably securing a curtain or the like thereto, a cornice or housing adapted to contain the pole and upper edge of the curtain, &c., and means secured within the housing for raising and lowering the pole into or from said housing, substantially as described. 80

4. In a curtain support, the combination of the pole embodying the parts B, B, cross bars S, S', extending between the bars B, B, and means for detachably securing a curtain or the like thereto, a cornice having the front 85 board K, top board L, and side boards M, M, pulleys Q, Q', secured to the top board within the cornice, and cords T, T', secured at one end to the cross bars S, S', passing over the pulleys and through an aperture U in one of 90 the side boards, the pole and fixtures being adapted to be entirely contained within the cornice, substantially as described.

Signed at New York, in the county of New York and State of New York, this 30th day 95 of August, 1895.

WILLIAM J. HEWITT.
